(57) **CLAIM**

We claim the ornamental design for a bicycle rack, as shown and described.

DESCRIPTION

FIG. 1 is a front elevational view of a first embodiment of the bicycle rack;

FIG. 2 is a side view of the bicycle rack illustrated in FIG. 1; FIG. 3 is a top view of the bicycle rack illustrated in FIG. 1; FIG. 4 is a side view of the bicycle rack illustrated in FIG. 1, turned 90 degrees from FIG. 2;

FIG. 5 is a front elevational view of a second embodiment of the bicycle rack;

FIG. 6 is a top view of the bicycle rack illustrated in FIG. 5; and,

FIG. 7 is a side view of the bicycle rack illustrated in FIG. 5, turned 90 degrees from FIG. 5.

The only difference between the second embodiment and the first embodiment is the addition of two identical rack elements.
